UNITED STATES PATENT OFFICE.

JOSEPH SOSS, OF BROOKLYN, NEW YORK.

HINGE.

1,019,096.

Specification of Letters Patent.

Patented Mar. 5, 1912.

Application filed December 30, 1911. Serial No. 688,661.

To all whom it may concern:

Be it known that I, JOSEPH Soss, a citizen of the United States, residing at Brooklyn, in the county of Kings and State of New York, have invented certain new and useful Improvements in Hinges, of which the following is a specification, such as will enable those skilled in the art to which it appertains to make and use the same.

10 This invention relates to hinges, and particularly to what are called invisible hinges, and more particularly to hinges of this class such as are described and shown in Letters Patent of the United States granted to me 15 Nov. 21, 1911, No. 1,009,108 and Dec. 26, 1911 No. 1,011,512. In the patent last named I have described and claimed a hinge of the class specified which will work in one direction only or in which the hinged door will 20 swing in one direction only and through an arc of 180 degrees, and one of the objects of this invention is to provide a hinge of the same class as that referred to in said patent and involving similar principles of 25 construction, and with which the door or other hinged member will swing in both directions and through an arc of 180 degrees; the further object of this invention being to provide a hinge of the class referred 30 to, and such as that shown and described in both of said patents, with the locking link or links which will prevent the door or other hinged member when in a closed position from moving away from the door-frame or 35 other stationary member. Said link or links being also applicable to the hinge described and claimed herein.

40 My present invention, or that forming the basis of this application is fully disclosed in the following specification of which the accompanying drawing forms a part, and in which the separate parts of my improvement are designated by suitable reference characters in each of the views, and in which,

45 Figure 1 is the side view showing my improved hinge applied to a door-frame and door, the door-frame and door, or parts thereof, being shown in section and parts of the hinge being broken away. Fig. 2 a 50 transverse section on the line 2—2 of Fig. 1 and indicated in dotted lines the swinging of the door in opposite directions; Fig. 3 a perspective view showing parts of the hinge 55 described and claimed herein detached; and Fig. 4 a view similar to Fig. 2 but showing the locking link device or devices applied to a hinge like that described and claimed in Patent No. 1,009,108 herein before referred to.

60 In the practice of my invention as shown in Figs. 1 to 3 inclusive I provide a hinge consisting of two main parts or butts *a* which in the accompanying drawing are secured one in the door frame *b* and the other in the door *b*². The said parts or butts *a* are provided centrally thereof and 65 at the back thereof with housings *a*² which are open at one side thereof and at the front and back thereof, the top and bottom of said housings being closed as shown at *a*³, these parts or butts *a* being of the same general 70 form as the corresponding parts shown in Patent No. 1,011,512 herein before referred to. In the patent last named I employ a floating link *d* consisting of straight bars having a 75 sliding connection with the hinge butts, but in this case I employ the floating links *c* which are substantially S-shaped in form and a plurality of which are shown, and these floating links *c* or the ends thereof extend into both of the housings *a*² and connected therewith at opposite sides of the center thereof are supplemental segmentally 80 curved links *d*, this connection being made by pins *e*. It will be seen that the links *d* are placed between the links *c* and the pins *e* do not extend into the main parts or butts *a*, but the other ends of the links *d* are connected with the parts or butts *a* by pins *f* 85 which are passed longitudinally through said parts or butts and which together with the supplemental links *d* carry the load or the hinged member. The ends of the links *c* which are extended into the housings *a*² of the main parts or butts *a* and which are curved in opposite directions are provided 90 with locking links *g* which are connected therewith by pins *h* and said locking links are connected with the closed sides of the housing *h* by pins *i* and the said closed sides of the housing *a*² are provided with recesses 95 in which the locking links *g* operate as clearly shown in Fig. 2. With this construction the door *b*² may be swung in both directions as indicated in said figure and the movable parts of the hinge will assume the position 100 indicated in dotted lines; and when the door

105

is closed as shown in said figure the locking links g will prevent movement of said door away from the frame b or in the plane of said door.

5 In Fig. 4 I have shown the locking links g applied to a hinge similar to that shown and described in the United States Letters Patent No. 1,009,108 hereinbefore referred to. In order to do this the arm members d^2 10 of the said hinge are slightly curved as shown in said figure and the locking links or link g are pivoted thereto at j and the said locking link or links are also pivoted to the closed side of the housing a^2 of the 15 main part or butt a into which the arms d^2 project the same as in the construction shown in Figs. 1 to 3 inclusive, and the hinge shown in Fig. 4 is also provided with links e^2 which correspond with the link 20 member or members e shown in said patent and which are pivoted to the closed sides of the housing in which the locking links g operate by means of the pin m and to the other part or butt member a by a pin n . 25 Said pin in the construction shown, being passed through the base of the arms d^2 . With this construction the door b^2 may be swung in one direction only and through an 30 arc of 90 degrees, but when the door is closed as shown in Fig. 4 the locking link or links g will prevent movement of the door away from the door-frame or in the plane of said door.

It will be understood that any desired 35 number of the links c , d and g may be employed in the construction shown in Fig. 4, with the exceptions of the details specified, the hinge construction here shown in Fig. 4, is the same as that shown in Patent No. 40 1,011,512; and it will be also understood that the locking links g may be applied to the construction shown in the Patent No. 1,011,512 if desired.

With the construction shown in Figs. 1 to 45 3 inclusive, it will be seen that the sliding connection of the floating links with the hinge butts made by means of pins passing through the end members of the floating links and movable in grooves in the top and bottom of the housings of the hinge butts as 50 shown in Patent No. 1,009,108 are omitted, the floating links in this case having no connection with the hinge butts except by means of the links d and g , but the floating links c 55 in this case may, if desired, have a sliding connection with the hinge butts as above set out and shown in Patent No. 1,009,108.

Although I have shown and described the 60 housings g^2 of the parts or butts a as open at one side and at the back thereof, it will be apparent that this form of said housings is not an essential feature and both sides and the back of said housings may be closed or partially so if desired.

Having fully described my invention what 65 I claim as new and desire to secure by Letters Patent is;

1. A hinge for connecting a swinging member with a stationary member, consisting of two main parts or butts connected by 70 movable parts and a locking device which prevents the swinging member from moving away from the stationary member when the swinging member is in a closed position.

2. A hinge for connecting a swinging 75 member with a stationary member, said hinge consisting of two main parts or butts having housings open at the front, said parts or butts being connected by movable parts mounted in said housings and provided with a locking device or devices which prevent the swinging member from moving away from the stationary member when the swinging member is in a closed position.

3. A hinge for connecting a swinging 80 member with a stationary member, said hinge consisting of two main parts or butts one of which is adapted to be secured to the stationary member and the other to the swinging member, said parts or butts being 85 connected by movable members only, and a locking device or devices which prevent the swinging member from moving away from the stationary member when the swinging member is in a closed position.

4. A hinge for connecting a swinging member with a stationary member, said hinge consisting of two main parts having 90 housings open at the front, said parts being connected by movable members mounted in 100 said housings and consisting partly of S-shaped floating links which are movable in both of said housings and a locking device or devices connected with said floating links and with said housings and which operate 105 to prevent the swing member from moving away from the stationary member when the swinging member is in a closed position.

5. A hinge for connecting a swinging member with a stationary member, said 110 hinge consisting of two parts connected by floating link devices, the swinging member being adapted to swing through an arc of 90 degrees in both directions.

6. A hinge for connecting a swinging 115 member with a stationary member, and consisting of two main parts connected by S-shaped floating link devices whereby the swinging member is adapted to swing through an arc of 90 degrees in both directions.

7. A hinge for connecting a swinging member with a stationary member, said hinge consisting of two parts connected by 12 S-shaped floating link devices whereby the swinging member is adapted to swing in both directions through an arc of 90 degrees, and locking link devices operating in

connection with said floating link devices to prevent the movement of the swinging member away from the stationary member when said swinging member is in a closed position.

5 In testimony that I claim the foregoing as my invention I have signed my name in

presence of the subscribing witnesses this 29th day of December 1911.

JOSEPH SOSS.
